[57] CLAIM

The ornamental design for a diagnostic test kit, as shown and described.

DESCRIPTION

FIG. 1 is an isometric view of a diagnostic test kit showing our new design;

FIG. 2 is a top plan view of the diagnostic test kit;

FIG. 3 is a front elevational view of the diagnostic test kit;

FIG. 4 is a left side elevational view of the diagnostic test kit;

FIG. 5 is a right side elevational view of the diagnostic test kit;

FIG. 6 is a rear elevational view of the diagnostic test kit;

FIG. 7 is a bottom plan view of the diagnostic test kit;
FIG. 8 is an exploded isometric view of the diagnostic test kit with its test stand cover, the cover of its first refill utensil tray, and one of its additional covers removed;

FIG. 9 is a top plan view of the diagnostic test kit taken from line 9—9 of FIG. 8;

FIG. 10 is an exploded isometric view of the diagnostic test kit without its test stand cover, the cover of its first refill utensil tray, or one of its additional covers, with its utensils and its first refill set of utensils removed;

FIG. 11 is a top plan view of the diagnostic test kit taken from line 11—11 of FIG. 10;

FIG. 12 is an exploded isometric view of the diagnostic test kit without its test stand cover, the cover of its first refill utensil tray, its first additional cover, its utensils, or its first refill set of utensils, with its test stand, its refill utensil trays, and its additional covers removed from its base;

FIG. 13 is a top plan view of the base of the diagnostic test kit, taken from line 13—13 of FIG. 12; and

FIG. 14 is a bottom plan view of a refill utensil tray, taken from line 14—14 of FIG. 12.
